UNITED STATES PATENT OFFICE.

JESSE SAMUEL BERNSTEIN AND LEONARD HULBERT, OF LONDON, ENGLAND; SAID HULBERT ASSIGNOR TO AUTOMATICKET LIMITED, OF LONDON, ENGLAND, A BRITISH COMPANY.

MACHINE FOR ISSUING PAPER AND PRINTED MATTER IN BOOKLET, CARD, TICKET, OR OTHER FORM.

Application filed April 27, 1923, Serial No. 635,165, and in Great Britain December 4, 1922.

This invention has reference to machines for issuing paper and printed matter in booklet, card, ticket or other form, the machines being of the kind embodying guides for the 5 passage of the paper or printed matter to the delivery outlet and a cutter for severing the paper or printed matter delivered from rolls or strips thereof, the strips or rolls being of the kind provided with apertures 10 in the length thereof.

In accordance with this invention the machine is provided with a device which serves for arresting the backward or return movement of the strip of paper or printed matter (hereinafter referred to as tickets) 15 towards the roll thereof. The device also serves for controlling the operation of the machine and indicating the exhaustion of a roll of tickets. The device is so constructed 20 and disposed as to project in the direction of the travel of and at an angle to the strip of tickets, and the aforesaid guide for the passage of the strip of tickets is provided with a recess or opening for the reception of 25 the forward end of the device after the passing of the last ticket the device moving to a position for effecting the actuation of a switch, valve, lever, or other suitable member for controlling the operation of the machine and a contrivance for indicating the 30 exhaustion of the said roll. The strip of tickets is fed intermittently towards the delivery outlet by a suitably mounted feed bar or member capable of successively engaging 35 with the apertures in the ticket in the forward movement and of disengaging therefrom on the return movement thereof for engagement with the next ensuing aperture. The apertures are preferably arranged at the 40 conjoined portions of the tickets, although it is to be understood that they may be provided at other parts of the tickets. The machine may be operated from one shaft provided with an eccentric or its equivalent 45 serving to operate the feed bar and also lever mechanism for reciprocating the cutter for severing the tickets from the strip, the cutter being detachably engaged with the lever

mechanism and held in place by a movable plate or frame for facilitating the removal 50 of the cutter and permitting either end thereof to be used for cutting the strip. To the same shaft may also be fitted a cam for actuating a spring or weight controlled lever operating in conjunction with a ticket gripping attachment which is in operation at the commencement of the cutting movement of the cutter and serves to hold the ticket to be severed from the strip. To prevent the withdrawal of a length of strip the machine is provided with mechanism whereby the strip is held against movement while a portion of the strip is in a position to be handled. Further, if desired the machine may be so provided as to prevent the strip or a portion thereof being handled except when a portion has been severed and constitutes a ticket. The machine may be provided with an indicator embodying movable plates, cards or similar members bearing 55 words such as directions or acknowledgements, and contrivances for rendering the plates or their equivalent alternately visible before and after the removal of a ticket, the preferred arrangement being such that two plates are employed capable of alternately occupying the same position and of being moved by a cam or its equivalent connected with a part of the machine or by the said gripping attachment. 60

In order that the said invention may be more clearly understood and readily carried into effect the same is hereinafter described more fully with reference to the accompanying drawings, wherein:—

Figures 1 and 2 are respectively side and end elevations of the machine constructed according to this invention.

Figure 3 is a similar view to Figure 1 showing the parts in a different position.

Figure 4 is a sectional elevation showing the interior of the machine with the internal parts shown in a position corresponding to the external parts shown in Figure 3.

Figure 5 is a plan view of Figure 3.

Figure 6 is a part sectional elevation of Figures 4 and 5 illustrating the position of the parts with strip of tickets in the guide.

Figure 7 is a perspective view to an enlarged scale of the ticket delivery outlet.

Figure 8 is a sectional elevation of the delivery outlet shown in Figure 7 and the indicator plate illustrating the position thereof relatively to the other part of the machine.

Figure 9 is a plan view of the indicator shown in Figure 8.

In the construction of the machine shown by way of example in the drawings the strip of tickets 10 forming part of a roll thereof is introduced into the lower end of the guide 11 and is intermittently moved upwardly or forwardly therein past the pivotally mounted arresting device 12 by the feed bar 13 and after the requisite movement of the strip has been effected the upper end of the strip is held against movement by the gripping attachment 14 and severed from the strip by the cutter 15. The guide 11 is secured at each end on pins 16 which serve to connect together two side plates 17 with the guide 11 between them the guide being provided with flanges 18 for maintaining the strip of tickets in position and with an aperture 19 for receiving the reduced or sharpened forward end 20 of the arresting device when the guide 11 is free of a strip of tickets, thus permitting the arresting device to be used in conjunction with other parts hereinafter referred to for arresting the operation of the machine upon the exhaustion of a roll of tickets. The strip of tickets is provided with spaced apertures 21 with which the feed bar 13 successively engages in intermediately moving the strip of the tickets forward the feed bar 13 being provided at its forward or free end with a pivoted finger 22 which is connected at its rear end to the feed bar 13 by a spring 23 serving to press the forward end of the finger against the strip of tickets and ensuring engagement with the successive apertures in the strip. The feed bar 13 is pivotally mounted at its rear or outer end on a pin 24 supported in the side plates 17 and is provided at a point intermediate of its ends with a stud 25 to which is pivotally connected one end of a link 26 the other end being pivotally connected to a strap 27 of an eccentric 28 mounted on a spindle 29 supported on the side plates 17. To the outer end of the spindle 29 is fitted a bevel wheel 30 as a means for imparting rotary motion thereto from a suitable power motor 100. The rotation of the eccentric 28 serves to move the feed bar 13 about the pin 24 to and from the upper end of the guide 11 and in the upward movement moves the strip of tickets in the guide by reason of the engagement of the forward end of the finger 22

with one of the apertures 21 in the strip and projects the free end of the strip 10 through an aperture 48 in a cutter plate 46. Upon reaching the upper end of the guide with the engaged aperture in line with the cutter 15 the movement of the feed bar 13 is reversed and it is returned to its initial position whereat the pivoted finger 22 engages with the succeeding aperture 21 of the strip of tickets. In its return to the initial position the spring controlled finger 22 passes in contact with the surface of the strip of tickets and in so doing tends to move the strip downwardly or rearwardly. Such downward or rearward movement of the strip is prevented by the pivotally mounted arresting device 12 the reduced or sharpened forward end 20 of which projects slightly upwardly and engages with the strip any tendency to downward or rearward movement having for effect in conjunction with a spring 64 by which the device is controlled to move the forward end 20 of the arresting device 12 closer to the guide 11 than is normally the case thus ensuring the strip being firmly gripped between the guide and arresting device. On the spindle 29 of the eccentric 28 is also mounted a cam 31 serving to operate a lever 32 pivoted at one end on a pin 33 secured to one of the side plates 17 and provided with a reduced free end 34 which co-acts with and moves a cam plate 35 a limited extent controlled by a slot 36 in one of the side plates 17 the cam plate 35 being provided with a pin 37 extending into such slot. The cam plate 35 is pivotally mounted at 38 on one of the side plates and operates an arm or a part 39 through a spring 40. The arm is connected with the gripping attachment 14 and is actuated by the movement of the cam operated lever 32 following the reversal of movement of the feed bar 13 at the upper end of the guide the reduced free end 34 of the lever 32 engaging with the cam plate 35 and moving the gripping attachment 14 towards the slot in a fixed plate 41 against the ticket fed upwards or forwards by the feed bar. In thus pressing the attachment 14 against the ticket 10 the spring 40 is placed in tension and the ticket is thereby firmly held during engagement of the cutter 15 with the strip 10 after which the reduced free end of the cam operated lever is moved to a position above the projecting portions of the cam plate 35. The operation of the cutter 15 is effected by a cranked lever 42 which is pivotally mounted at its lower end on a rod 43 supported at each end in the side plates 17 and is actuated by the eccentric 28 which is extended to one side of the strap 27 as shown in Figure 2 and alternately engages with rollers 44 mounted on projections 45 provided on the cranked lever 42 on opposite sides of the eccentric 28. With such

an arrangement the cranked lever 42 is rocked about the rod 43 and imparts intermittent reciprocatory motion to the cutter 15 for the purpose of severing portions from the strip of tickets.

The cutter is mounted on the cutter plate 46 which is arranged at the upper end of the side plates 17 and is provided with guideways 47 for the engagement of the sides of the cutter therewith. In the cutter 15 is provided two slots 49 to enable either of the cutting edges 50 at the opposite ends of the cutter 15 to be used for severing the tickets from the strip the upper end of the cranked lever 42 engaging with the slot 49 corresponding to the cutting edge 50 in use. To facilitate changing the cutter or reversing the position of the cutting edges the cutter is held in position between the guideways 47 by a plate spring 51 pivotally secured to the cutter plate 46 by a pin 52 such plate spring being movable to one side clear of the cutter for this purpose. After the ticket has been severed from the strip it is held in position against the fixed plate 41 by the gripping attachment 14 and in thus being held the pivoted arm 39 is pressed towards the cam operated lever 32 and holds the cam plate against the reduced end of such lever 32 through the spring 40. In thus being held against the reduced end of the cam operated lever 32 the cam plate prevents such lever being returned to its initial position by a spring 53. The cam accordingly moves out of contact with the lever 32 and in so doing breaks an electric circuit whereby the operation of the machine is effected or controlled. In the event of the ticket being removed from the gripping attachment the pivoted arm or member 39 is released allowing the cam plate to be moved by the reduced end of the cam operated lever which accordingly is returned into contact with the cam by the spring 53. The operation of the machine may be effected by an electric motor through gearing engaged with the bevel wheel 30 or by any other convenient form of power motor controlled by an electrically operated switch. The circuit of such electric motor or switch which as before mentioned is adapted to be broken by the cam 31 moving out of contact with the lever 32 includes a spring contact plate 54 arranged on an insulation block 55 secured to one of the side plates 17, the cam 31, against the face of which bears the spring contact plate 54 a plate 56 which is mounted on an insulation plate 57 secured to the cam operated lever 32 and bears against the periphery of the cam 31 and the leads 58. By the arrangement of the electric contact between the cam 31 and the lever 32 and the co-operation of the gripping attachment 14 therewith as herein described it will be understood that the machine is adapted to op-

erate as the severed tickets are removed, the successive operations of the feed bar 13, gripping attachment and cutter being effected until the roll or strip of tickets is exhausted and the end of the strip has passed the arresting device 12, whereupon the arresting device is free to return to the position shown in Figure 4 and such return takes place when the cam operated lever 32 is in a raised position which permits an arm 59 attached to or forming part of the arresting device to move beneath the lever 32 and the arresting device to its initial position. The movement of the arresting device 12, as hereinbefore explained, takes place about the pivot pins 61 and is effected by the spring 64. In thus being moved to its initial position, the arresting device 12 engages at its forward end with the aperture 19, owing to the rear end of the apertured strip having passed the forward end of the arresting device. The arm 59 attached to the device 12 moves therewith and becomes disposed in the position shown in Figure 3 beneath the lever 32, having been moved from the position shown in Fig. 6 by the device 12 and its spring 64. This movement occurs during the presence of a ticket or an end portion in the delivery outlet when the lever 32 is in the raised position. The presence of the arm 59 beneath the cam operated lever 32 prevents the latter being returned to its initial position by its spring 53 and accordingly the cam 31 moves out of contact therewith and the circuit of the operating motor or controlling switch broken. The lower end of the arm 59 extends through an opening 60 in one of the side plates 17 and the arresting device 12 is mounted on the pivot pins 61 supported in the said side plates. To indicate the exhaustion of a roll of tickets the arm 59 is fitted with an insulated contact piece 62 and the spring contact plate 54 is formed with a spring contact tongue 63 capable of engaging with the contact piece 62 when the arm 59 is held out of engagement with the cam operated lever 32 by the arresting device 12 bearing on a strip of tickets in the guide 11. The engagement of the tongue 63 with the contact pieces 62 completes an electric circuit including an electric lamp which serves to indicate that the machine is in operative order with the strip of tickets in position. Upon the arm 59 moving to a position beneath the cam operated lever 32 the contact piece 62 moves out of engagement with the tongue 63 and thus the circuit is broken and the lamp extinguished. To facilitate the movement of the arm 59 and contact piece 62 relatively to the spring contact tongue 63 the arresting device is so mounted as to be capable of moving a limited extent laterally between the side plates 17 and to ensure contact between the tongue 63 and

piece 62 when the parts are in the requisite position for this purpose the arresting device is connected to one of the side plates 17 by the aforesaid spring 64 which is disposed obliquely to the side plates and tends to move the arresting device towards the side plate to which the spring is attached. In connection with the electric lamp circuit including the tongue 63 and contact piece 10 62 is provided other electric lamps for illuminating an indicator fitting embodied with the delivery outlet 65 having an opening 66 through which the severed ticket partly projects when held by the gripping attachment. The delivery outlet 65 is also provided with a glazed opening 67 in connection with which the indicator fitting is so arranged as to permit either of two plates 68 of the indicator frame 69 to be visible. 15 The plates 68 may be inscribed with any suitable words or figures such as for example the words "Takit" and "Thank you" and are adapted to be moved to the desired positions respectively upon the appearance 20 of a ticket at the delivery outlet and the removal of it therefrom. The frame 69 is pivotally mounted on the side plates 17 by pins 70 being fitted with a lever arm 71 having a curved end 72 with which engages an 25 eccentric pin 73 on a disc 74 mounted on the spindle 29 of the cam 31. The rotation of the disc 74 serves to operate the frame 69 against the action of a spring 75 connected to the upper wall 76 of the casing 30 of the machine by a bracket 77. To effect the movement of the indicator fitting without the same being easily discerned the lamps by which the plates 68 are illuminated are extinguished during such movement. 35 For this purpose the electric circuits of the lamps for illuminating the plates 68 of the indicator fitting are provided with spring contact fingers 78 against one or the other of which the lever arm 71 bears when the indicator is in one or the other of its set positions the electric circuit being completed by a spring contact brush 79 engaging with the disc 74. By this arrangement the circuit is broken during the movement 40 of the indicator frame 69 and the lamps extinguished. The lamps may be arranged outside the case in a suitable position to illuminate the plates from the front or the plates may be in the form of stencils or 45 transparencies and illuminated from the rear by lamps disposed within the case of the machine.

60 The mechanism herein described is serviceable for the issue of cards, tickets, booklets with one or more insert leaflets therein or other forms of paper or printed matter delivered and severed from single rolls thereof. For the issue of booklets with one or 65 more inserts therein folded strips enclosing single strips are introduced into and passed

through the guides and severed into lengths forming booklets. The machine may be adapted for use in multiple for the concurrent issue of two or more strips or rolls of paper or printed matter.

To prevent the withdrawal of a length of the strip 10 embodying a number of tickets before the cutter comes into operation and thereby obviate possible fraud the strip is engaged by a holding mechanism capable of successively engaging with parts or apertures of the strip and preventing withdrawal of the same. The holding mechanism embodies a lever 80 (Figure 4) mounted on a pivot pin 81 supported at each end in the side plates 17. The upper end of the lever 80 is provided with an inclined or cam shaped edge 82 for the engagement therewith of the inner end of the feed bar 13 when approaching its lowest position for the engagement of the pivoted finger 22 with a succeeding aperture 21. The engagement of the inner end of the feed bar 13 with the lever 80 moves the latter about its pivot and disengages a pin 83 provided on the lower end of the lever 80 from an aperture 10 in the strip thereby releasing the strip and allowing it to be fed forward by the feed bar 13. This release of the strip does not take place however until after the cutter has come into operation and therefore any attempt to withdraw a length of strip will be prevented by either the holding mechanism or the cutter. Preferably the guide is formed with a recess or opening 84 for the reception of the pin 83. To facilitate the introduction of a strip of tickets into the guide the movement of the pin 83 from the path of the strip is effected by pressure applied to the outer end of the arresting device which pressure moves it about the pivot bearings 61 and removes the reduced forward end 20 from the path of such strip. In thus moving the arresting device a free passage is provided for the strip. The operation of the lever 80 by the arresting device 12 is effected through the medium of a pin 85 bearing against the device and attached to a part 86 which is provided on the lever 80 and serves to move it to a position in which the pin 83 engages with the aperture 84. The withdrawal of a length of strip may be further prevented by devices for surrounding or enclosing the projecting portion of the strip and lifting the ticket after it has been severed from the strip to a position in which it may be taken from the machine. To this end the delivery outlet is fitted with an upstanding plate 87 (Figure 7) having returned or inwardly projecting side edges 88 which serve to support a transparent plate or member 89 in such a position as to provide a passage for a ticket after the same has been severed from the strip and also serve to surround or enclose the pro- 130

jecting portion of the strip before the same is severed for constituting a ticket, the upper end of the strip being so disposed below the upper edge of the plates 87 and 89 that it cannot be taken hold of by the hand. After the ticket has been severed from the strip it is projected upwardly by a spring controlled lifting finger 90 pivotally mounted on the free end of a bar 91 pivoted at 92 to ears on the cutter plate 46 and fitted at an intermediate point in its length with a roller 93 capable of being engaged by the cutter 15 upon its return movement after severing a ticket from the strip. The engagement of the cutter with the roller 93 raises the free end of the bar 91 and causes the free end of the lifting finger 90 to engage with the ticket and project a portion of it above the upper end of the plates 87 and 89 to a position in which it may be handled. To ensure the free end of the lifting finger 90 engaging the ticket it is provided with a toothed or sharpened edge and the ticket is supported against the fixed plate 41 which preferably extends to the orifice of the outlet fitting as shown in Figure 8. If desired the plate 87 may be provided with an inscription such as "Thank you" visible through the transparent plate 89 after the removal of a ticket.

What we claim and desire to secure by Letters Patent of the United States is:—

1. In a machine for issuing tickets from an apertured strip thereof, the combination of a delivery outlet, a power motor, a shaft driven thereby, a rotary cam on the said shaft, a spring controlled member operated by the said rotary cam, motor control means connected with the cam and the member, means for holding the member against operation when an end portion of the strip is in the delivery outlet and automatically operated means for rendering the member inoperative when the apertured strip is exhausted.

2. In a machine for issuing tickets from an apertured strip thereof, the combination of a delivery outlet, a power motor, a shaft driven thereby, a rotary cam on the said shaft, a spring controlled member operated by the said rotary cam, motor control means connected with the member and the cam, an attachment which serves for holding an end portion of the strip in the delivery outlet, a cam plate connected with the attachment for preventing the operation of the member when an end portion is in the outlet, a guide for the strip of apertured paper the guide being provided with an aperture, a spring controlled device which serves for arresting rearward movement of the strip and engages with the aperture in the guide in the absence of the strip, and an extension attached to the arresting device capable of automatically engaging with the said member

and holding it against operation when the arresting device engages with the aperture in the guide upon the exhaustion of the apertured strip.

3. In a machine for issuing tickets from an apertured strip thereof, the combination of a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, an eccentric on the said shaft for operating the feeding arm and the cutter, means for holding the member against operation when an end portion is in the delivery outlet and automatically operated means for rendering the member inoperative when the apertured strip is exhausted.

4. In a machine for issuing tickets from an apertured strip thereof, the combination of a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, an eccentric for positively operating the feeding arm and the pivotally mounted lever, means for holding the member against operation and rendering the machine inoperative when an end portion is in the delivery outlet and automatic means capable of rendering the member and the machine inoperative when the apertured strip is exhausted.

5. In a machine for issuing tickets from an apertured strip thereof, the combination of a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, a pivotally mounted lever connected to the cutter, an eccentric for positively operating the feeding arm and the pivotally mounted lever, an attachment which serves for holding end portions in the delivery outlet and embodies a cam plate for preventing the operation of the said member and of the machine when an end portion is in the delivery outlet, a

guide for the strip of apertured paper the guide being formed with an aperture, a spring controlled device which serves for arresting rearward movement of the strip and engages with the aperture in the guide in the absence of the apertured strip, and an extension on the arresting device which automatically engages the said member for holding it against operation and rendering the machine inoperative upon the exhaustion of the apertured strip.

6. In a machine for issuing tickets from an apertured strip thereof, the combination of a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, a pivotally mounted lever connected to the cutter, an eccentric for positively operating the feeding arm and the pivotally mounted lever, a finger operated by the cutter for lifting an end portion in the delivery outlet, means for holding the member against operation when a ticket is in the delivery outlet and automatic means for rendering the member and the machine inoperative when the apertured strip is exhausted.
10. 7. In a machine for issuing tickets from an apertured strip thereof, comprising a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, a pivotally mounted lever connected to the cutter, an eccentric for positively operating the feeding arm and the pivotally mounted lever, a finger operated by the cutter for limiting the severed end portions in the delivery outlet, an attachment which serves for holding end portions in the delivery outlet and embodies a cam plate for preventing the operation of the said member when an end portion is in the delivery outlet, a guide for the strip of apertured paper the guide being formed with an aperture, a spring controlled device which serves for arresting rearward movement of the strip and engages with the aperture in the guide in the absence of the apertured strip, and an extension which is provided on the arresting device and automatically engages the said member for holding it against operation and rendering the machine inoperative upon the exhaustion of the apertured strip.
15. 8. In a machine for issuing tickets from an apertured strip thereof, the combination of a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, a pivotally mounted lever connected to the cutter, an eccentric for positively operating the feeding arm and the pivotally mounted lever, a passage adjoining the delivery outlet and provided with a transparent window for exhibiting end portions, an attachment which serves for holding an end portion in the delivery outlet and embodies a cam plate for preventing the operation of the said member when an end portion is in the delivery outlet, a guide for the strip of apertured paper the guide being formed with an aperture, a spring controlled device which serves for arresting rearward movement of the strip and engages with the aperture in the guide in the absence of the apertured strip, and an extension on the arresting device which automatically engages with the said member and holds it against operation and thereby renders the machine inoperative upon the exhaustion of the apertured strip.
20. 9. In a machine for issuing tickets from an apertured strip thereof, the combination of a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, a pivotally mounted lever connected to the cutter, an eccentric for positively operating the feeding arm and the pivotally mounted lever, a device capable of being actuated by the feeding arm for holding the apertured strip against forward movement, means for holding the member against operation, automatically operated means for rendering the member and the machine inoperative when a ticket is in the delivery outlet and when the apertured strip is exhausted.
25. 10. In a machine for issuing tickets from an apertured strip thereof, the combination of a delivery outlet, a power driven shaft, a rotary cam on the said shaft, a spring controlled member operated by the said rotary cam and embodying means for regulating the operation of the machine, an arm for feeding the apertured strip, a cutter for severing end portions from the strip, a pivotally mounted lever connected to the cutter, an eccentric for positively operating the feeding arm and the pivotally mounted lever, a device capable of being actuated by the feeding arm for holding the apertured strip against forward movement, a finger actuated by the cutter for lifting the end portions in the delivery outlet, a passage adjoining the delivery outlet and provided with a transparent window for exhibiting end portions, an attachment which serves for holding an end portion in the delivery outlet and embodies a cam plate for preventing the operation of the said member when an end portion is in the delivery outlet, a guide for the strip of apertured paper the guide being formed with an aperture, a spring controlled device which serves for arresting rearward movement of the strip and engages with the aperture in the guide in the absence of the apertured strip, and an extension on the arresting device which automatically engages with the said member and holds it against operation and thereby renders the machine inoperative upon the exhaustion of the apertured strip.
30. 11. In a machine for issuing tickets from an apertured strip, the combination of a delivery outlet, a strip feeding mechanism, a cutting mechanism for severing an end

portion from the strip, a motor control mechanism subject to the presence of an end portion in the outlet, a mechanism to prevent reverse movement of the strip, and an automatic mechanism which co-acts with the control mechanism and the strip reverse movement preventing mechanism to render the machine inoperative when the strip is exhausted.

12. In a machine for issuing tickets from an apertured strip, the combination of a delivery outlet, a mechanism for feeding the strip to the outlet, a cutting mechanism capable of co-acting with the outlet for severing an end portion from the strip fed to the outlet, a motor control mechanism subject to the presence of the end portion in the outlet, a mechanism to prevent reverse movement of the strip when the latter is not being fed to the outlet by the feeding mechanism, a mechanism which co-acts with the feeding mechanism to positively hold the strip against fraudulent removal thereof, and an automatic mechanism which is actuated by the mechanism for preventing reverse movement of the strip and co-acts with the control mechanism to render the machine inoperative when the strip is exhausted.

13. In a machine for issuing tickets from an apertured strip, the combination of a delivery outlet, a mechanism for feeding the strip to the outlet, a cutting mechanism capable of co-acting with the outlet for severing an end portion from the strip fed to the outlet, a motor control mechanism subject to the presence of the end portion in the outlet, a mechanism to prevent reverse movement of the strip when the latter is not being fed to the outlet by the feeding mechanism, a mechanism which co-acts with the feeding mechanism to positively hold the strip against movement in either direction, a mechanism which co-acts with the cutting mechanism to lift the severed end portion in the delivery outlet, and an automatic mechanism which is actuated by the mechanism for preventing reverse movement of the strip and co-acts with the control mechanism to render the machine inoperative when the strip is exhausted.

14. In a machine for issuing tickets from an apertured strip, the combination of an oscillatable strip feeding mechanism, a reciprocated cutting mechanism which co-operates with the feeding mechanism and serves to sever an end portion from the strip, a delivery outlet capable of enclosing the severed end portion, a motor control mechanism subject to the presence of the end portion in the delivery outlet, a mechanism to prevent reverse movement of the strip when the latter is not being fed to the delivery outlet by the feeding mechanism, a mechanism for lifting the severed end portion to a withdrawal position in the delivery

outlet, a mechanism operated by the feeding mechanism to positively engage the strip and prevent fraudulent withdrawal of a length thereof, and a mechanism which renders the other mechanisms inoperative and is automatically operated by the mechanism for preventing reverse movement of the strip and engages with and arrests the operation of the motor control mechanism upon the exhaustion of the strip.

15. A machine for issuing tickets from an apertured strip thereof, comprising a delivery outlet, means for feeding the strip to the outlet, a cutting mechanism which co-operates with the feeding means and severs an end portion from the strip fed to the outlet, an attachment for holding the severed end portion in the delivery outlet, a member capable of co-acting with the attachment for rendering the feeding means inoperative when an end portion is in the delivery outlet, a mechanism for preventing reverse movement of the strip when it is not being fed to the outlet by the feeding means, and a means which is operable by the mechanism for preventing reverse movement of the strip and engages with the member and arrests the operation of the machine thereby in the absence of a severed end portion in the delivery outlet upon the exhaustion of the apertured strip of tickets.

16. A machine for issuing tickets from an apertured strip thereof, comprising a delivery outlet, means for feeding the strip to the outlet, a cutting mechanism which co-operates with the feeding means and serves to sever an end portion from the strip, a spring controlled attachment for holding the end portion in the delivery outlet, a spring controlled member which co-acts with the attachment for arresting the operation of the machine when an end portion is in the outlet, a rotary cam for moving the member in opposition to its spring, a mechanism for preventing reverse movement of the strip when it is not being fed by the feeding means to the outlet, and a means which is operated by the mechanism for preventing reverse movement of the strip and is engaged with the member and thereby arrests the operation of the machine in the absence of an end portion in the said outlet and upon the exhaustion of the said strip.

17. A machine for issuing tickets from an apertured strip thereof, comprising a delivery outlet, means for feeding the strip to the outlet, a cutting mechanism which co-operates with the feeding means and serves to sever an end portion from the strip, an attachment which is provided with a spring controlled cam plate and serves for holding the end portion in the outlet, a spring controlled member which co-acts with the cam plate for arresting the operation of the machine when an end portion is in the delivery

outlet, a rotary cam which moves the member in opposition to its spring, a mechanism for preventing reverse movement of the strip when it is not being fed by the feeding means to the outlet, and a means which is operated by the mechanism for preventing reverse movement of the strip and is en-

gaged with the member and holds it against movement for arresting the operation of the machine in the absence of an end portion in the outlet and upon the exhaustion of the apertured strip.

JESSE SAMUEL BERNSTEIN.
LEONARD HULBERT.

CERTIFICATE OF CORRECTION.

Patent No. 1,635,171.

Granted July 12, 1927, to

JESSE SAMUEL BERNSTEIN ET AL

It is hereby certified that error appears in the printed specification of the above numbered patent requiring correction as follows: Page 2, line 3, after "with" insert the article "a"; same page, line 40, for the word "intermediately" read "intermittently"; page 6, line 32, claim 7, for the word "limiting" read "lifting"; same page, lines 87, 88 and 89, claim 9, strike out the words "automatically operated means for rendering the member and the machine inoperative" and insert the same after the word "and" in line 90, of same page and claim, and that the said Letters Patent should be read with these corrections therein that the same may conform to the record of the case in the Patent Office.

Signed and sealed this 30th day of August, A. D. 1927.

Seal.

M. J. Moore,
Acting Commissioner of Patents.
